Primary Examiner — Dana L Meyrow(74) *Attorney, Agent, or Firm* — Gary J. Foose**CLAIM**

(57) The ornamental design for a package for laundry additive, as shown and described.

DESCRIPTION

FIG. 1 is a top perspective view of a package for laundry additive showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines in the drawings illustrate the portions of the design that form no part of the claim.
